DECORATED ARTICLE

Lucifer J. Most, Arlington, N. J., assignor to Metals & Controls Corporation, Attleboro, Mass., a corporation of Massachusetts

Application February 18, 1937, Serial No. 126,379

1 Claim. (Cl. 41—34)

This invention relates to decorated articles, and with regard to certain more specific features, to metallic articles, such as bracelets, wrist watch straps, watch cases, necklaces, and the like, decorated with inlays of plastic material.

Among the several objects of the invention may be noted the provision of decorated articles of the class described wherein the decorative plastic material is firmly interlocked with the article itself, passing therethrough and being headed over in the manner of a rivet; the provision of a decorated article of the class described wherein the decorations are not likely to come loose and fall from the article; and the provision of decorated articles of the class described, which are relatively simple and economical to produce. Other objects will be in part obvious and in part pointed out hereinafter.

The invention accordingly comprises the elements and combinations of elements, and features of structure, which will be exemplified in the articles hereinafter described, and the scope of the application of which will be indicated in the following claim.

25 In the accompanying drawing, in which is illustrated one of the various possible embodiments of the invention,

Fig. 1 is a perspective view of stock to be decorated;

30 Fig. 2 is a perspective view of the stock of Fig. 1 after a first operation thereon;

Fig. 3 is a cross section of the stock of Fig. 2, showing a sheet of plastic material in position for a molding operation;

35 Fig. 4 is a perspective view of a pressure molding device;

Fig. 5 is a cross section similar to Fig. 3, illustrating the stock after it has been subjected to an operation in the apparatus of Fig. 4; and,

40 Fig. 6 is a plan view of a wrist watch band embodying decorated stock made in accordance with the present invention.

Similar reference characters indicate corresponding parts throughout the several views of the drawing.

45 In the past, it has been possible to carry out decorating work of the character comprehended by the present invention only by the complicated processes of marquetry, the plastic decorations being cemented in place after having been shaped to closely fit routings made to receive them. In addition to being difficult, this method is not wholly satisfactory in that the cement often loosens and the decorative pieces fall out 50 of their sockets and are lost.

Similar processes, such as the filling of designs impressed or indented in outline in the article to be decorated, with paints, enamels, and the like, are also used, but these are generally considered inferior to a real inlay, being less satisfactory 5 in appearance and being subject to cracking and chipping in usage.

According to the present invention, inlays may be made with relative simplicity, and when so accomplished, are attractive in appearance and 10 strongly attached to the article so decorated.

In the accompanying drawing, the various figures illustrate the steps of the present invention as applied to the decoration of a wrist watch strap of the link type, which may be said to be 15 typical of the articles which can be decorated, but which is not to be considered in a limiting sense.

Numeral 1 in Fig. 1 indicates link stock in strip form, such as is commonly produced by 20 rolling operations and used in the manufacture of straps and bracelets. The stock 1 comprises relatively thick edge regions 3 and a relatively thin central portion 5.

Fig. 2 shows the same stock after it has been provided with openings 7 of the size and shape desired for the inlaying process, such openings in this case being made at spaced intervals by stamping and perforating dies in a series of repetitive steps. While the particular openings 7 shown in Fig. 2 are in the form of a circle, it will be apparent that openings of any other shapes can be made in the same manner, by using stamping and perforating dies having the outline desired.

30 Each opening 7 is provided, on the face of stock 1, with a concentric recess 9, the purpose of which will be explained later.

When the stock 1 has been so prepared, a layer 40 of plastic material, as indicated at numeral 11 in Fig. 3 is placed along the under side of the stock 1. The assembly of plastic material 11 and perforated stock 1 is then placed in a suitable pressure device such as that shown in Fig. 4.

45 Referring to Fig. 4, numeral 13 indicates the lower half of the pressure device, and is provided with recesses 15 of suitable shape to receive the regions 3 on the under side of the assembly shown in Fig. 3. In carrying out the invention with articles of shape other than that shown in the several figures of the drawing, it is understood that the pressure device of Fig. 4 is made to correspond with whatever shape of article or article stock may be employed. Passage 17 in Fig. 4 is 50 a lengthwise opening in the lower half 13 of 55

pressure device 11 to permit the introduction of steam, water, or similar fluids for the purpose of heating and cooling the pressure device as desired, connections 19 to passage 17 being provided for this purpose.

The pressure device being shown in part in the drawing, valves for supplying and controlling heating agents have been omitted. These, however, are quite well known in use and application 10 in the plastic molding art, which is akin to the present invention, and their illustration in detail is therefore felt to be unnecessary.

In Fig. 4, numeral 21 indicates the upper half of the pressure device corresponding to lower half 13, which upper half is provided with edge grooves 23, likewise of a shape to fit the particular stock to be processed. Passage 25 in half 21 is also a lengthwise opening permitting the circulation of suitable agents for the heating and 20 cooling of upper half 21, and, like passage 17 in the lower half 13, is provided with connections 27. The half 21 is also shown but in part, valves as required being provided in the usual manner for the supply and control of the agents 25 used.

After the assembly of Fig. 3 has been placed in position in the lower half 13 of the pressure device, the upper half 21 is positioned on top of the assembly, and the whole is put into a suitable press capable of forcing the lower and upper halves together. Steam or other suitable heating means is then permitted to flow through openings 17 and 25, causing lower and upper halves 13 and 21 to become heated, and to transmit some of this heat to the assembly of Fig. 3 in place between them. This causes softening of the plastic material 11, so that when the lower and upper halves 13 and 21 are forced together in the press, pressure is exerted on softened material 40 11 which forces it to flow into openings 7 of stock 1. The heating agent circulating in passages 17 and 25 is then shut off and in its place, by means of suitably arranged valves, a cooling agent is directed, which chills the lower and upper halves 45 13 and 21 of the pressure device and causes the inlaid plastic to harden.

Referring to Fig. 5, numeral 29 indicates the position now taken by plastic material 11, completely filling in openings 7. It will be observed that some of plastic material 11 still remains in place on the bottom side of stock 1, serving to lock itself therewith on this side. On the other side, recess 9, which is now filled with plastic material, serves as a lock, so that inlaid plastic material 29 is tightly held in place without the use 55 of a separate adhesive.

When stock 1 is thus inlaid with plastic material, it is, in the present instance which depicts a wrist watch strap, cut into individual pieces 31

(Fig. 6) for the forming of the several links, and further processed according to methods usually employed in their manufacture. Fig. 6 shows the appearance of a completed link strap for a wrist watch, made up of a series of joined members of which numerals 31 indicate the inlaid pieces made from stock 1, numerals 33 indicate the attachments to join with the watch case, and numeral 35 indicates the buckle for opening and closing the strap when attached to a watch. 5

There are many variations which can be made in the process and article as described and shown herein without departing from the scope of the invention. 10

For example, design elements of plastic material can be given on the top or exposed side a 15 figuration in relief such as a rosette or similar embellishment, by suitably engraving at properly spaced intervals the upper half 2 of the pressure device in the negative. Or, instead of using 20 recess 9 as a top locking means, upper half 21 of the pressure device can be provided with properly shaped recesses spaced to register with the cut out sections of stock 1, so that when the plastic material flows under heat and pressure, 25 it will head up over the top surface of the stock 1.

The present invention applies to any plastic material that is initially in a coherent form, and which becomes soft or moldable under the application of heat pressure. Suitable plastic materials, for example, comprise Celluloid plastics, 30 phenolic condensation resinoids, and the like.

In view of the above, it will be seen that the several objects of the invention are achieved and other advantageous results attained. 35

As many changes could be made in carrying out the above constructions without departing from the scope of the invention, it is intended that all matter contained in the above description or shown in the accompanying drawing shall 40 be interpreted as illustrative and not in a limiting sense. 45

I claim:

A decorated article comprising a metallic base having an opening therethrough, and plastic material extending through said opening and provided with a head on each side of the said base, whereby said plastic material is locked in position on said base, said base being provided with a recess aligned with said opening on one side of said base, the head of plastic material on that side of the base being located entirely in the said recess, and presenting a surface substantially continuous with the surface of that side of the base, the head of plastic material on the other side of the base presenting a surface parallel to that of said other side of the base. 55
